J. U. DE UHERKOCZ.

LIFE PRESERVER.

APPLICATION FILED JAN. 2, 1908.

906,340.

Patented Dec. 8, 1908.

UNITED STATES PATENT OFFICE.

JULIUS UHERKOVICH DE UHERKÓCZ, OF BAYONNE, NEW JERSEY.

LIFE-PRESERVER.

No. 906,340.

Specification of Letters Patent.

Patented Dec. 8, 1908.

Application filed January 2, 1908. Serial No. 408,935.

To all whom it may concern:

Be it known that I, JULIUS UHERKOVICH DE UHERKÓCZ, a citizen of the United States, residing at Bayonne city, in the county of 5 Hudson and State of New Jersey, have invented certain new and useful Improvements in Life-Preservers, of which the following is a specification.

My invention relates to improvements in 10 life preservers in which an expanding and collapsible bag, expanded by means of hinged braces or ribs of wood or other material within the same, is distended and the bag stretched for the purpose of holding air.

15 And more especially to those forms of life preservers in which the sustaining power is obtained by means of air drawn into a hollow body when the same is expanded, by means of an open tube which is then closed 20 and the air within said distended or expanded device escapes again as the air-valve is opened at the will of the operator.

I elect to use in the operation of my device any kind of flexible material for the air bag 25 and for the covering of the same, preferably a canvas lined with oil or other water-proof coating and impervious to air or water; also any kind of material for the ribs or braces within the same, which may be suitable.

30 The purpose of my invention is to produce a light, cheap, sure form of device, easily handled or carried, ready for instant use for sustaining the body while in the water and capable of being compressed into the smallest 35 possible space for the purpose of being carried when not in use.

With this and other objects in view my invention comprises certain novel constructions, combinations and arrangement of 40 parts as hereinafter more particularly described.

Figure 1 is a perspective view showing the invention in position. Fig. 2 is a front view partly in section, said section being taken on 45 line 2 2 of Fig. 3. Fig. 3 is a sectional plan view taken on line 3 3 of Fig. 2. Fig. 4 is an enlarged cross section similar to the sectional portion of Fig. 2. Fig. 5 is a plan view of my invention showing the device 50 partly collapsed or inflated.

My invention consists of an elongated circular bag made of canvas or other pliable material, lined with an oil coating or other lining in which are a series of ribs of wood or 55 other stiff material as shown in Figs. 2, 3 and 4.

In the body portion "A" I have a series of ribs consisting of two series of members, one series being a vertical brace or rib and the other a series of curved ribs or braces. The 60 end of each rib, that is the vertical rib 1 and the curved rib 2, is covered by an overlapping canvas strip 3 3 and 4 4 respectively as shown in Fig. 4. This overlapping canvas is stitched to the outer covering 5 on 65 the braces 1 and 2. Brace 1 is placed upright against the curved brace 2 as shown in Fig. 4. Over the outside of brace 1 and brace 2, is stretched the outside canvas or covering 5 5 as shown in Figs. 4 and 5. The 70 said series of braces are equi-distant within the canvas covering as shown in Fig. 3. In the center of the perpendicular brace 1, and the semi-circular brace 2 there is attached a flexible band of cloth or other material 6 6 75 and 6', 6' as shown in Figs. 3 and 4. The canvas covering 5 5 is firmly attached to each of the ribs or braces 1 and 2. The ends of these ribs or braces form a flexible union at points 7 and 8 as shown in Figs. 2 and 4. 80 When not in use on the person, the elongated bag is collapsed or contracted together as shown in Fig. 5. At each end of the bag are the eyelets 9 9 as shown in Figs. 2 and 3. When the operator desires to use the same 85 he brings the elongated bag around his body as shown in Fig. 1, and ties the bag by means of strings as shown in Figs. 2 and 3. Also attached to the body portion are the shoulder straps 10 10 as shown in Fig. 2. When the 90 body portion is untied and is in a partially collapsed position it appears as shown in Fig. 5.

To the body portion I have attached a small metal tube 11, with a screw-cap upon 95 the same as shown in Fig. 2. In the operation of my device, in order to expand the bag I open the tube 11 and pull out the bag to its full length. I then fasten the cap on the tube 11. In this way the air within the bag 100 cannot escape. Having brought the ends of the now-expanding bag around together in circular form and having fastened them by tying the strings 9 9 as shown in Figs. 2 and 3, the circular bag is then passed over the 105 body and the arms passed through the shoulder-straps 10 10 as shown in Fig. 1, and the life preserver is then ready for use.

Having thus described my invention what I claim as new and for which I desire Letters 110 Patent, is as follows:

1. A life preserver comprising a flexible

covering, ribs in the covering arranged in pairs and the ribs of each pair having their ends flexibly joined by the covering, strips holding the ribs properly spaced, and strips fitted over the ends of the ribs.

2. A life preserver comprising a flexible covering, ribs arranged in pairs in the covering and each pair consisting of a straight inner rib and a curved outer rib, strips looped over the ends of the ribs, spacing strips hold-

ing the pairs of ribs in spaced relation, an inlet pipe connected to the covering, and a screw cap closure to the pipe.

In testimony whereof I have affixed my signature, in presence of two witnesses.

JULIUS UHERKOVICH DE UHERKÓCZ.

Witnesses:

H. T. WALKER,
H. F. ROSE.
